UNITED STATES PATENT OFFICE.

OTHELius J. OLSEN, OF PORTLAND, OREGON.

CARPENTER'S SQUARE.

1,333,128.

Specification of Letters Patent. Patented Mar. 9, 1920.

Application filed June 23, 1919. Serial No. 306,115.

To all whom it may concern:

Be it known that I, OTHELius J. OLSEN, a citizen of the United States, residing at Portland, in the county of Multnomah and State of Oregon, have invented a new and useful Carpenter's Square, of which the following is a specification.

My invention relates to improvements in squares in which one member is provided with leveling tubes for horizontal and vertical leveling, and where the other member may be detached when not in use.

The objects of my invention are:

First, to give the carpenter a tool at his disposal which permits both squaring and leveling.

Second, to combine in my machine utility with strength without ponderosity.

Third, to provide a tool which can conveniently be stored in any ordinary tool chest.

I attain these objects with the mechanism illustrated in the accompanying drawing in which—

25 Figure I is a plan view of the entire square;

Fig. II is a partial side view of the removable tongue;

30 Fig. III is a section through Fig. I along the line *a—a*.

Fig. IV is a section through Fig. I along the line *b—b*.

Similar numerals refer to similar parts throughout the several views.

35 My square comprises two separable members which, for the sake of identification, may be designated as main member and tongue.

The main member is of hollow construction and details thereof appear in the sections Figs. III and IV, where it is shown that the top plate 1 and the side plates 2 are bent of one single piece of sheet steel; the channel formed thereby is covered by an other strip of sheet steel, viz, the bottom plate 3. Rivets 4, spaced at suitable intervals, hold the two plates together. Separators 5, used in connection with the rivets where necessary, insure the proper distance

50 between the two plates.

Three leveling tubes 6 are inserted in the hollow space between the plates 1 and 3, the one in the center being positioned for hori-

zontal leveling and the other two for vertical leveling. Openings 6^a in the top and bottom plates must, of course, be provided for the observation of the leveling tubes.

The tongue is fashioned of solid metal, and appears in side view (Fig. II) somewhat tapering toward the end 7 and has 60 the other end 8 provided with a tenon 9 which extends longitudinally of the tongue. Said tenon slides in a corresponding mortise in the main member, the mortise walls 10 being part of the top plate 1 and bent down 65 to the required taper as illustrated in Fig. III.

A pawl 11 at the end of the tenon 9 engages a recess 12 in the top plate 1 and prevents involuntary separation of the tongue 70 from the main member.

With the tongue withdrawn it becomes a simple matter to store both parts in an ordinary tool chest.

Having thus described my invention it 75 will be seen that my objects have been accomplished and, though I have shown the preferred form of construction, I reserve to myself the right to make minor changes, providing I do not violate the spirit and 80 principle of my invention.

I claim:

1. In a carpenter's square, the combination of one long member and one short member at right angles to the long member and 85 forming an integral part thereof, having the top and side plates bent of one single piece, having a cover plate at the bottom riveted to the top plate, and having a mortise in the end of the short member longitudinally of said member, with a removable extension member of solid construction, having a tenon at one end longitudinally of said extension member, and capable of being slidably mounted within the mortise 90 of the short member.

2. In a carpenter's square, the combination of a hollow main member, having the top plate at one end split and bent inwardly to form a mortise, with a removable solid extension member having a tenon at one end and capable of being slidably mounted within the mortise of the main member.

Signed by me at Portland, in the State of Oregon, this 17th day of June, 1919.

OTHELius J. OLSEN.
